ber 23, 1927, Serial No. 242,168. Renewed Sep-
tember 25, 1931

7 Claims. (Cl. 248—31)

This application is a division of my co-pending application for patent for Conductor clamps, filed June 17th, 1927 and given Serial No. 199,512.

The invention relates to clamps such as are used for the suspension of the conductors of transmission lines, for securing a ground conductor, and for other purposes.

In transmission line practice it is customary to provide conductor clamps which are pivoted with respect to the insulator string from which the conductor is suspended. The pivot point of the clamp is generally several inches from the suspension device and the result is that when the clamp moves in accordance with vibrations of the conductor the clamp must move longitudinally as well as pivotally. As such clamps are necessarily of fairly heavy construction so as to withstand the service strains they have considerable inertia and will not follow the vibrations of the conductor. It consequently occurs that the conductor may bend more or less sharply at the edge of the clamp, resulting in crystallization and eventual breaking of the conductor strands. It therefore becomes a matter of importance to reduce the inertia so that the clamp may respond instantly and accurately to the vibrations which are always present in the transmission line.

It is with the above facts in view that I have designed the present invention which has for its principal object the provision of a clamp so constructed and having such a pivotal mounting that it will offer the minimum resistance to the conductor vibrations, that is to say the inertia will be reduced so that the clamp may follow the vibrations without lagging and causing bending strains in the conductor to be set up.

The object of the invention, more specifically stated, is to provide a clamp pivoted on an axis transverse to and intersecting the longitudinal axis of the conductor whereby necessary movement in a vertical plane will be permitted without changing the location of the center of mass of the clamp and without any change in the position of the supporting parts above it.

Still another object of the invention is to provide a clamp of such construction that there will be a rolling rather than a sliding contact at the pivot so as to facilitate oscillation.

Another object of the invention is to provide a clamp structure embodying these principles of design, it being possible that the clamp be employed not only for the suspension of a conductor but also for effecting mounting of a ground conductor upon a pole, the particular pivot arrangement being such as to permit the clamp to follow

the conductor during the vibrations thereof and also regardless of the inevitable weaving of the pole or equivalent support.

A further object is to provide a clamp having a novel arrangement of pivot means and a novel mounting therefor on the suspension means whereby assembly, or disassembly, may be effected quickly and easily.

An additional object is to provide a clamp of this character which will be simple and inexpensive to manufacture, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawing in which:

Figure 1 is a side elevation of the device constructed as a suspension clamp,

Figure 2 is a plan view thereof showing it arranged for pivotal mounting upon a pole or other support, and

Figure 3 is an end elevation of the device mounted upon the pole and with the conductor in cross section.

Referring more particularly to the drawing, the numerals 23 and 24 designate the upper and lower clamping members respectively which are disposable upon opposite sides of the conductor or cable 25 and which are concaved or grooved in the usual manner for substantially conforming engagement therewith, the end portions of 90 the grooves flaring outwardly away from the conductor to provide what may be called bell mouths. The lower clamping member 23 is represented as provided with laterally extending apertured lugs or ears 26 for the passage of the U-bolts 27 which are located upon seats 28 defined between pairs of transverse ribs 29 on the upper clamping member 23. The central portion of the upper clamping member may be reinforced by a longitudinally extending rib or web 30. Of course the U-bolts 100 27 carry nuts 31 to provide the securing action.

It is preferable that the lower clamping member 23 have its intermediate or central portion upwardly extended and that the upper clamping member be similarly shaped, thus making the conductor receiving groove or passage of serpentine form as clearly illustrated in Figure 1 for the purpose of avoiding the pivot bolt 32 which passes through a suitable opening 33 in the lower clamping member, this opening having its axis inter- 110

secting the longitudinal axis of the conductor and located at right angles thereto. Obviously, the conductor must be warped or sprung out of its longitudinal line as indicated as otherwise it 5 would interfere with the bolt and it is for this reason that the conductor receiving groove or passage is made serpentine in shape.

It is readily conceivable that the clamp when constructed in this manner may be connected 10 with suspension links 16 as illustrated in the parent application of which this case is a division, and in such event the through bolt 32 would pass through suitable openings such as those indicated at 21 in Figure 1. However, there is another use 15 for this form of clamp, namely its employment as a means for securing a ground conductor upon the top portion of a pole or the like indicated at 34. Mounted in this manner, the bolt 32 would be carried, for instance, by a curved plate 35 secured to the pole in some suitable manner, nuts 20 36 being threaded onto the bolt at opposite sides of the clamp for maintaining the latter in proper position for pivotal movement without danger of its contacting the pole. In other words the clamp 25 is intended to be spaced away from the pole to a sufficient extent that it may have the necessary free pivotal movement.

In the use of this clamp, it is of course apparent that it is engaged with the conductor by disposing 30 the members 23 and 24 upon opposite sides thereof, inserting the U-bolts 27 through the apertured ears or lugs 26 and then applying the nuts 31 and drawing them down to effect the necessary clamping action upon the conductor. In 35 case the device is used as a suspension clamp, the links 16 are used and the connection therewith made by means of the bolt 32, and if the clamp is used in mounted position upon a pole the bolt attached to the curved plate is passed 40 through the clamp. In either event the arrangement is such that pivotal action will occur freely so as to permit the clamp to accommodate itself to vibratory or other unavoidable incidental movements of the conductor without exerting 45 any bending strains thereon which might result in crystallization and eventual separation of the fibers thereof possibly as the result of molecular friction.

From the foregoing description and a study of 50 the drawing it will be apparent that I have thus provided a simply constructed and inexpensive clamp which may be quickly and easily assembled or disassembled and which will in every way possess the advantages and perform the functions above outlined. Experience has demonstrated that a conductor mounted by means of clamps of this character will possess unusual durability on account of the absence of bending strains.

60 While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

70 Having thus described the invention, I claim:

1. In a clamping device of the character described, upper and lower clamping members disposable at opposite sides of and having aligned seat portions engageable with a conductor, means 75 for maintaining said clamping members in

clamping relation to the conductor, and a pivot bolt passing substantially centrally through one clamping member transversely thereof with its axis intersecting the longitudinal axis of said aligned seat portions, both clamping members having intermediate seat portions offset with respect to the pivot bolt for maintaining the conductor out of obstructing relation to the bolt. 80

2. In a device of the character described, a pair 85 of clamping members disposable at opposite sides of a conductor having mating aligned straight seat portions engageable therewith, one clamping member having its central portion formed with a transverse opening, means located at opposite sides of the opening for maintaining the clamping members in clamping relation to the conductor, and a pivot bolt passing through said opening, the axis of the opening and pivot bolt intersecting the longitudinal axis of the mating seat portions at right angles, the clamping members having means thereon for maintaining the intermediate clamped portion of the conductor in a position curved away from the pivot bolt to avoid obstruction therewith. 95

3. In a clamping device of the character described, upper and lower clamping members disposable upon opposite sides of a conductor and having their confronting faces grooved for substantially conforming engagement with the conductor, the end portions of the grooves being 105 straight and aligned and means for mounting the clamping device including a bolt passing transversely through the one clamping member and having its axis intersecting and at substantially right angles to the longitudinal axis of the 110 grooves at the ends of the clamp, the intermediate portions of the confronting grooved faces of the upper and lower clamping members being of serpentine form whereby the conductor will occupy a position out of obstructing relation to 115 said bolt.

4. In a clamping device of the character described, upper and lower clamping members disposable upon opposite sides of a conductor and having their confronting faces grooved for substantially conforming engagement with the conductor, the end portions of the grooves being straight, means for mounting the clamping device including a bolt passing transversely through the lower clamping member and having 125 its axis intersecting and at substantially right angles to the longitudinal axis of the grooves at the ends of the clamp, the confronting grooved faces of the intermediate portions of the upper and lower clamping members being of serpentine 130 form whereby the conductor will occupy a position out of obstructing relation to said bolt, the lower clamping member having laterally extending apertured ears, the upper clamping member having spaced seats thereon opposite said ears, 135 and clamping bolts engaging the seats, passing through the ears and carrying securing nuts.

5. In a clamping device of the character described, upper and lower clamping members disposable at opposite sides of a conductor, means 140 for maintaining said clamping members in clamping relation to the conductor, pivot means for the lower clamping member having its axis intersecting the normal axis of the conductor, said clamping members having seat portions off- 145 set with respect to the axis of the pivot means.

6. In a clamping device of the character described, upper and lower clamping members disposable at opposite sides of a conductor, means for maintaining said clamping members in clamp- 150

ing relation to the conductor, pivot means for the assembled clamping members having its axis transverse to and intersecting the normal longitudinal axis of the conductor, said clamping members having seat portions arranged to maintain the conductor out of intersecting relation to the axis of the pivot means at the center of the assembled clamping members.

7. In a clamping device of the character described, upper and lower clamping members disposable at opposite sides of a conductor, means

for maintaining said clamping members in clamping relation to the conductor, pivot means located between said maintaining means for supporting the assembled clamping members, said pivot means being located with its axis at right angles to and in intersecting relation to the normal longitudinal axis of the conductor beyond the ends of the clamping device but out of intersecting relation thereto within the confines of the clamping device.
